UNITED STATES PATENT OFFICE

2,137,363

FURNACE FOR MELTING FINE AND
GRANULAR SUBSTANCES

Arthur Sprenger, Berlin-Halensee, Germany, assignor to the firm Chemische Studien-Gesellschaft Uniwapo G. m. b. H., Berlin, Germany

Application November 2, 1937, Serial No. 172,483
In Germany November 14, 1936

8 Claims. (Cl. 263—32)

This invention relates to improved furnaces for melting fine and granular substances.

Many fine and granular substances when heated tend to adopt a doughy or pasty state before melting. It is difficult to melt substances of this kind because the grains at the surface become doughy and tend to frit together and thus to form a heat protective layer which prevents the layers underneath from being effectively heated. This applies not only where the fine or granular material is introduced into the furnace in lots but also if it is fed and melted continuously, in the usual manner.

It is the object of the present invention to avoid this difficulty in melting such material.

According to the invention the furnace comprises at least one zone for preheating fine and granular material, at least one tapping zone, at least two inclined surfaces intermediate said preheating and tapping zones, said inclined surfaces having a slope adapted to retain the unmelted material and to allow the melted material to run down to said tapping zone and means for intermittently and successively delivering unmelted material to said surfaces from the preheating zone.

Further objects and particulars of the invention will be clear from the following detailed description in connection with the accompanying drawings showing by way of example and schematically some embodiments of furnaces according to the invention, viz—

Figure 1 is a vertical section through a furnace according to the invention, on line I—I of Figure 2.

Figure 2 shows on the left hand side a horizontal section on the bent line II—II of Figure 1 and, on the right hand side, a plan view of the furnace shown in Figure 1.

Figure 3 is a partial section on line III—III in Figure 2.

Figure 4 is a vertical section in part of another embodiment of the furnace on line IV—IV in Figure 5.

Figure 5 is a vertical section on the bent line V—V of Figure 4.

Figure 6 is a horizontal section of a third form of construction of the furnace.

Figure 7 is a horizontal section through a fourth form of construction of a furnace according to line VII—VII of Figure 8.

Figure 8 is a vertical section on the bent line VIII—VIII of Figure 7.

Figure 9 is a vertical section through a fifth

form of construction of a furnace on line IX—IX of Figure 10.

Figure 10 is a vertical section on line X—X of Figure 9.

Referring to Figures 1 to 3, showing a furnace with regenerative gas firing, the heating gas is fed to the nozzles *a* without being preheated or warmed up. The air for the combustion is preheated in chambers *b* in front of which large slag chambers *c* are arranged. For the sake of clarity the switching system and the duct system have not been shown.

It will be seen that the furnace has two separate tapping zones *d* and *d'*, which are independently heated by means of horse-shoe-shaped or U-shaped flames (Figure 2) a portion of which is guided over the melting zones consisting of inclined surfaces *e* and *e'*. The upper part of this surface is more inclined than the lower part thereof.

The heating gases come together behind the melting zones *e* and *e'* and pass through a duct *f* into the preheating zone, which in this special embodiment of the invention is comprised by a rotary tube furnace or revolving tubular kiln *g*.

The intermittent charging of the melting zone is effected by changing the direction of rotation of the drum of the furnace *g* at periodical intervals so that the preheated material will be discharged alternately onto the area *e* or the area *e'*.

In order to provide for a better control of the intermittent charging or feeding, a control member may be used as shown in Figures 4 and 5. The control member in this instance consists of an inclined guide face *h*, which is mounted on a vertical rotary spindle *h'*. The material falling from the drum of the furnace *g* onto the guide face is directed onto that portion of the melting hearth which is just free from material that is being melted.

By means of such a control member, the preheated material may be selectively delivered not only in two directions but in a plurality of directions, without the necessity of changing the direction of rotation of the drum of the furnace *g*.

The furnace shown in Figure 6 comprises three melting zones *e*, *e'* and *e''* and three tapping zones *d*, *d'* and *d''*.

In this instance a simple firing by means of gases of a high calorific value or by means of coal dust without preheated air is advantageously used instead of regenerative firing. The temperature in the drum of the furnace *g* should not reach the melting temperature.

The number of melting zones and tapping zones may be increased to such an extent that the single zones are arranged immediately adjacent to each other and form a pyramid or cone shaped body.

5 In the Figures 9 and 10 a furnace is represented, in which the melting zone *e* and the tapping zone *d* form a conical body.

In the embodiment shown in Figures 7 and 8 slide members *i*, *i'* are used instead of a rotary 10 control member, which members move the material that has been preheated in the drum of the furnace *g* into either of the melting zones *e* or *e'*. In order to simplify the movement of these slide members, the longitudinal axes of the 15 two melting zones *e*, *e'* and of the coordinate tapping zones *d*, *d'* have been arranged at right angles to each other.

While I have herein shown and described certain preferred embodiments of my invention, I 20 wish it to be understood that I do not confine myself to all the precise details herein set forth by way of illustration, as modification and variation may be made without departing from the spirit of the invention or exceeding the scope of 25 the appended claims.

Having now described my invention what I claim is:—

1. In a melting furnace in combination, at 30 least one zone for preheating fine and granular material, at least one tapping zone, at least two inclined surfaces intermediate said preheating and tapping zones, said inclined surfaces having a slope adapted to retain the unmelted material and to allow the melted material to run 35 down to said tapping zone and means for intermittently and successively delivering unmelted material to said surfaces from the preheating zone.

2. In a melting furnace in combination, at 40 least one zone for preheating fine and granular material, at least one tapping zone, at least two inclined surfaces the upper portion of which is more inclined than the lower portion thereof and which surfaces are arranged intermediate said 45 preheating and tapping zones, said inclined surfaces having a slope adapted to retain the unmelted material and to allow the melted material to run down to said tapping zone and means for intermittently and successively delivering unmelted material to said surfaces from the preheating zone.

3. In a melting furnace in combination, at 50 least one zone for preheating fine and granular material, at least one tapping zone, inclined surfaces in the form of a pyramid arranged intermediate said preheating and tapping zones, said inclined surfaces having a slope adapted to retain the unmelted material and to allow the melted material to run down to said tapping zone, and means for intermittently and success-

sively delivering unmelted material to said surfaces from the preheating zone.

4. In a melting furnace in combination at 5 least one zone for preheating fine and granular material, at least one tapping zone, a cone arranged intermediate said preheating and tapping zones, said cone having a slope adapted to retain the unmelted material and to allow the melted material to run down said cone and means for intermittently and successively delivering unmelted material to the single portions of said cone from the preheating zone.

5. In a melting furnace in combination, at 10 least one zone for preheating fine and granular material, a plurality of tapping zones, a plurality 15 of inclined surfaces intermediate said preheating and tapping zones, said inclined surfaces having a slope adapted to retain the unmelted material and to allow the melted material to run down to said tapping zones and means for intermittently and successively delivering unmelted material to said surfaces from the preheating zone.

6. In a melting furnace in combination, at 20 least one zone for preheating fine and granular material, a plurality of tapping zones, a plurality 25 of inclined surfaces intermediate said preheating and tapping zones, said inclined surfaces having a slope adapted to retain the unmelted material and to allow the melted material to run down to said tapping zones and means for intermittently and successively delivering unmelted material to said surfaces from the preheating zone.

7. In a melting furnace in combination, a zone 30 for preheating fine and granular material, a plurality of tapping zones, a plurality of inclined surfaces intermediate said preheating and tapping zones, said inclined surfaces having a slope 35 adapted to retain the unmelted material and to allow the melted material to run down to said tapping zones, and a plurality of slide members 40 coordinated to and adapted for, charging each inclined surface intermittently with unmelted 45 material from the preheating zone.

8. In a melting furnace in combination, at 50 least one revolving tubular kiln for preheating fine and granular material, two tapping zones, two inclined surfaces each between each of said 55 tapping zones and said revolving tubular kiln, said inclined surfaces having a slope adapted to retain the unmelted material and to allow the melted material to run down to said tapping zones, which kiln includes a drum and means 60 adapted to rotate said drum in either direction, for delivering said fine and granular material intermittently on either of said two inclined surfaces.

ARTHUR SPRENGER. 60
